(57) **CLAIM**

The ornamental design for a welding machine shell as shown and described.

DESCRIPTION

FIG. 1 is a perspective view of a welding machine shell showing my new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 1; and,

FIG. 10 is an enlarged view of the encircled area 10 of FIG. 2.

The broken lines shown on the drawings depict portions of the welding machine shell that form no part of the claimed design.
